UNITED STATES PATENT OFFICE.

WILLIAM EARLE BROCK, OF PETROLIA, ONTARIO, CANADA.

PUMP.

Application filed September 6, 1924. Serial No. 736,292.

To all whom it may concern:

Be it known that I, WILLIAM EARLE BROCK, a citizen of Canada, residing at Petrolia, in the Province of Ontario and 5 Dominion of Canada, have invented new and useful Improvements in Pumps, of which the following is a specification.

This invention relates to pumps, and contemplates a structure which eliminates the 10 use of a pump rod, the piston remaining stationary while the barrel of the pump is reciprocated, the invention being extremely simple in construction and readily accessible for inspection or repair as the case 15 may be.

The nature and advantages of the invention will be better understood when the following detailed description is read in connection with the accompanying drawings, 20 the invention residing in the construction, combination and arrangement of parts as claimed.

In the drawings forming part of this application, like numerals of reference indicate similar parts in the several views, and wherein:

Figure 1 is a vertical sectional view through the structure forming the subject matter of the present invention.

Figure 2 is a sectional view taken on line 2-2 of Figure 1,

Figure 3 is a sectional view on line 3-3 of Figure 1,

Figure 4 is a sectional view on line 4-4 of Figure 1,

Figure 5 is a sectional view on line 5-5 of Figure 1.

Referring to the drawings in detail 10 indicates the well casing provided with a 40 top or cover 11, the latter constituting a base to support a hollow standard made up of a plurality of packing glands and coupled as clearly illustrated in Figure 1.

For instance, rising from the cover 11 is a 45 hollow boss 12 to which is secured the adjacent part 13 of a packing gland, the other component part of which is indicated at 14.

The part 14 is fitted within the part 13, and interposed between these parts is the packing 50 15. Suitable fastening elements 16 are used to secure the part 13 to the hollow boss. The part 13 has threaded or otherwise suitably secured thereto a sleeve like member 17, the upper end of which is connected with a coupling 18 having an outlet nipple 19 which constitutes the outlet for

the pump. This coupling 18 has screwed or otherwise suitably secured thereto the adjacent part 19 of a packing gland, the other part of which is indicated at 20. 60 This part 20 of course fits within the part 19, and interposed between said parts is the packing 21 as clearly shown. The component parts 19 and 20 of this packing gland are secured together by bolts or other 65 suitable fastening elements 22.

A tubing 23 of any suitable dimension is passed through this hollow standard composed of the elements just described, and entering the well casing 10, and is adapted 70 to be reciprocated when use of the pump is desired. The upper end of this tubing is closed by a headed plug 24, and rising from this plug is a hook like element 25 by means of which the tubing can be reciprocated for 75 the purpose specified. Coupled as at 26 to the lower end of the tubing 23 is a short length of pipe 27 which in turn is secured to a larger coupling sleeve 28, the lower end of which receives a short length of pipe 29. 80 The upper end of this pipe is normally closed by a check valve 30 which is used in a manner and for a purpose to be presently described. The lower end of the pipe 29 is coupled as at 31 to the upper end of the 85 pump barrel 32, which barrel is provided with a plurality of fluid inlet openings 33. In this connection it will also be noted that the tubing 23 is provided with a plurality of outlet openings 34. Secured to the lower 90 end of the barrel 32 is a coupling sleeve 35 which is slidably mounted on a short rod 36, the upper end of which has secured thereto a stationary piston 37 wholly positioned within the barrel 32. The rod 36 95 may be of any suitable length and has secured to the lower end thereof a weight 37 which is adapted to rest or repose upon the bottom of the well, and thus maintain the piston 37 stationary.

In practice, the piston is held stationary in the manner just stated and when the barrel 32 is moved upwardly from its lowermost position, a suction is created in the barrel, so that when the openings 33 pass 105 beyond the piston, the fluid is drawn into the barrel as will be readily understood. When the barrel is moved downwardly, the piston forces the water from the barrel through the short pipe 29 into the tubing 111 23, the check valve 30 closing after each operation to prevent back pressure, or re-

turn of the water to the barrel as will be readily appreciated. The water when forced upwardly through the tubing 23 is finally discharged therefrom through the 5 openings 34 into the discharge nipple 19 above referred to. The construction is not only very simple, but the pump can be conveniently and easily manipulated in the manner and for the purpose specified, and 10 by eliminating the use of a reciprocatory piston rod, the pump can be conveniently removed from the well for inspection or repair as the case may require.

While it is believed that from the foregoing description, the nature and advantages of the invention will be readily apparent, I desire to have it understood that I do not limit myself to what is herein shown and described, and that such changes may 20 be resorted to when desired as fall within the scope of what is claimed.

What I claim is:

In combination, a well casing, a cover therefor, a hollow standard rising from the

cover and including a plurality of packing glands and coupling members suitably secured together, a tubing arranged to reciprocate through said standard and well casing, and having a plurality of outlet openings positioned at an appropriate point in its length, a discharge nipple projecting from said standard, a pump barrel arranged beneath and in align with said tubing and having a plurality of fluid inlet openings at an appropriate point in its length, means for coupling the said barrel with the lower end of said tubing, a check valve arranged above said barrel, a stationary piston arranged within the barrel, a rod depending from said piston, and a weight carried by the lower end of the rod for holding said piston stationary while said barrel is reciprocated for the purpose specified.

In testimony whereof I affix my signature.

WILLIAM EARLE BROCK.
